(57) **CLAIM**

The ornamental design for a medicament delivery device, as shown and described.

DESCRIPTION

FIG. 1 is a perspective view of a medicament delivery device showing our new design;

FIG. 2 is another perspective view thereof;

FIG. 3 is an end view thereof;

FIG. 4 is another end view thereof;

FIG. 5 is a side view thereof;

FIG. 6 is another side view thereof;

FIG. 7 is another side view thereof; and,

FIG. 8 is another side view thereof.

The broken lines in the figures show portions of the medicament delivery device which form no part of the claimed design.
